UNITED STATES PATENT OFFICE.

ARTHUR B. GOODSPED, OF CHESTER, CONNECTICUT.

OIL BURNER.

Application filed June 6, 1924. Serial No. 718,230.

In another application of the present applicant for Letters Patent of the United States, Serial No. 655,386, filed August 3, 1923, there are shown and described certain improvements in oil burners. In that application a requirement was made on the part of the Commissioner of Patents for division on the ground that the claims were drawn to several independent inventions. The present application is made primarily for the purpose of complying with that requirement and for covering one of such independent inventions, but in the time which elapsed between the filing of said earlier application and the making of such requirement for division, the construction which formed the subject matter of the said earlier application as filed was further developed and perfected and the present application, therefore, while covering the original independent invention, is based upon the perfected construction and is addressed in part to the perfected features. The invention which is the subject of this application, is concerned particularly with the construction of the burner itself, the control of the supply of oil and water to the burner being covered in another application Serial No. 718,229 filed June 6, 1924.

In the burner which forms the subject of the present application, as in the burner which was shown and described in said application Serial No. 655,386, the oil is delivered at the burner tip, not in a vaporized form, as in many oil burners, but in a liquid form and is taken up, carried on, sprayed and vaporized by a surrounding envelope of superheated steam. This result requires a certain construction of the burner proper, as will be described hereinafter. Furthermore, the maintenance of constant regulated pressure under which the oil is discharged is essential to the control of the temperature and to perfect combustion and for the accomplishment of these purposes it has been found desirable to do away with the means for adjusting the steam orifice, as described in said application Serial No. 655,386, and to provide a stabilizing valve through which any excess of superheated steam developed in the generator, instead of being discharged from the generator at a point where it will mingle with the hot products of combustion at the tip of the flame, is returned to the burner nozzle where it is added to the steam directly supplied thereto, in propor-

tion to the consumption of oil and, through the resulting tendency to increase of temperature and pressure, reacts through the pressure controlled oil and water supply to cut down the supply of both oil and water, thereby maintaining the internal temperature in the combustion chamber and the pressure in the generator substantially constant. The invention will be more fully described hereinafter with reference to the accompanying drawing, the single figure of which shows, partly in elevation and partly in vertical section, a complete burner and generator in which the invention is embodied.

The improved means for controlling the supply of oil and water under substantially constant pressure are fully described in the application Serial No. 718,229 filed June 6, 1925 and for present purposes it is sufficient to say that the oil is supplied under substantially constant pressure through a pipe a' which is tapped into a base c , channeled as at c' . The base is preferably formed, as described in said application Serial No. 655,386, with a conical seat c^2 to receive a conical liner d which in turn is formed with a conical seat d' to receive a conical member e which supports the burner tip e' . The conical liner is channeled as at d^2 and the burner support is channeled as at e^2 to permit the oil to be delivered to the orifice e^3 of the burner tip which, as will be observed and as is necessary to the proper delivery of the oil, is slightly higher than the plane of the steam orifices by which it is surrounded as hereinafter described, thus permitting the discharge of oil at the orifice e^3 in liquid form and the complete filling of the conducting channels, to the orifice e^3 , with oil in liquid form. The liner d , flanged as shown at d^4 , may be secured to the base c by screw bolts not shown, and the burner tip supporter e may be secured to the liner by screw bolts e^4 and so held in place. The burner tip supporter e may also be provided with a removable plug e^5 for convenience in manufacture and in cleaning out. It will be observed that the burner tip e' has an external diameter less than the internal diameter of the bore of the sleeve extension of the liner d , so as to form a chamber d^6 about the burner tip e' for the admission of superheated steam from the generator, to be described. Upon the sleeve extension of the liner d is threaded a sleeve f conical at its

upper end to form at f' an annular orifice surrounding the burner tip e^3 but at a slightly lower level. In the embodiment of the invention shown in the application Serial No. 655,386, the corresponding sleeve was made adjustable by hand, for the purpose of varying the steam orifice, but in the present construction this is unnecessary and when the burner parts have once been assembled and properly adjusted, further adjustment of the sleeve f is unnecessary. The sleeve f , as will be observed, forms a continuation of the chamber d^6 about the burner tip.

15 Also supported upon the sleeve f and spaced therefrom so as to form a chamber f^2 , is a sleeve f^3 also conical at its upper end and forming an annular steam orifice f^4 surrounding the oral orifice e^3 and the primary stem f' , the chamber f^2 being supplied with excess steam from the generator as herein-after described.

Water, under constant head as described in said application Serial No. 718,229, filed June 6, 1924 is supplied through a pipe g' to a channel g^2 in one of the radial lugs or arms of the base c , whence it is delivered through a pipe g^3 to the generator h . Superheated steam from the generator h is delivered through a pipe h' , which rises within the generator nearly to the top thereof, and a pipe h^2 to a channel h^3 in one of the radial lugs or arms of the base c , whence it is delivered through a channel h^4 to the chamber d^6 about the burner tip e' . In the embodiment of the invention shown in the application Serial No. 655,386, any excess of steam, developed and superheated in the generator h , is delivered into an annular channel about the upper part of the chimney sleeve l , whence it is allowed to mingle with the hot products of combustion as they issue through openings beneath the refractory top o . In the present instance, however, it has been found desirable, in order to maintain a substantially uniform internal temperature about the generator, and a substantially constant pressure within while providing a safety outlet for the excess steam, to return such excess steam to a point where it may be mingled with the steam from the primary steam orifice f' and with the oil from the oil orifice e^3 . Accordingly, the excess steam is conducted from the channel h^4 , through a suitable connector h^5 , to a stabilizing valve h^6 which receives the steam through an inlet h^7 , upon which rests a spherical valve body h^8 , the weight of which may be supplemented as desired by a weight h^9 supported in the closed weight chamber h^{10} . From the valve chamber such steam as passes the valve h^6 is delivered through a suitable conductor h^{11} to the chamber f^2 which terminates in the sec-

ondary, annular steam orifice f^4 about the primary steam orifice f' and the oil orifice e^3 . Thereby excess pressure within the generator may be relieved through the stabilizing valve h^6 and the excess steam is delivered to the burner nozzle, through the secondary steam orifice f^4 , and there mingles with the steam through the primary steam orifice f' and with the oil from the oil orifice e^3 . The surplus steam therefore supplies steam in proportion to the consumption of oil and, with the oil, tends to increase the internal temperature below the generator and therefore the pressure within the generator. Through the pressure actuated devices for controlling the flow of oil and water, the flow of each is cut down and the tendency toward a rise of temperature below the generator and of the pressure in the generator is counteracted and substantially uniform temperature is maintained under given conditions.

It will be understood that changes in details of construction and arrangement can be made to suit different conditions of use and that, except as pointed out in the claims, the invention is not restricted to the particular construction shown and described herein.

I claim as my invention:

1. In an oil burner, the combination of a burner tip, means to supply oil thereto, a steam generator, a sleeve forming a steam chamber about the burner tip and having an annular orifice about the burner tip, a second sleeve forming a second steam chamber about the first mentioned sleeve and having an annular orifice, means to conduct steam from the generator to the first mentioned steam chamber and other means, including a stabilizing valve, to conduct steam from the generator to the second named steam chamber.

2. In an oil burner, the combination of a burner tip, means to supply oil thereto, a steam generator, a sleeve forming a steam chamber about the burner tip and having an annular orifice about the burner tip, a second sleeve forming a second steam chamber about the first mentioned sleeve and having an annular orifice, means to conduct steam from the generator to the first mentioned steam chamber and other means, including a stabilizing valve, to conduct steam from the generator to the second named steam chamber, said stabilizing valve comprising a chamber connected on one side to the generator and on the other side to the second named steam chamber and a weighted valve body to control the passage of steam therethrough.

This specification signed this 3d day of June, A. D. 1924.

ARTHUR B. GOODSPEED.
